UNITED STATES PATENT OFFICE.

CHARLES NEVATT, OF GLASGOW, SCOTLAND.

WINDOW-BLIND FITTING.

Application filed January 12, 1924. Serial No. 685,894.

To all whom it may concern:

Be it known that I, CHARLES NEVATT, 23 Darnley Gardens, Pollokshields, Glasgow, Scotland, a subject of the King of Great Britain, have invented certain new and useful Improvements Relating to Window-Blind Fittings, of which the following is a specification.

My invention relates to improvements in window blind fittings of the kind comprising a blind roller having journals at its ends one of which is receivable in a jaw member carried by a bracket, a ratchet wheel held under spring pressure on the jaw engaging journal, and a detent or escapement device attached to said bracket for engagement with said ratchet wheel.

The objects of my improvements are, first, to provide a roller blind of the character stated such that the blind proper will, in use, be equally spaced from either side of the window; second, to prevent the blind cord fouling or becoming entangled during winding or unwinding; third, to eliminate axial movement of the blind roller and therefore accidental displacement of the same from its bearings; and fourth, to provide a roller blind the parts of which can be quickly and easily erected, dismantled or renewed as and when required without requiring any special skill.

I attain these objects by the mechanism illustrated in the accompanying drawing, in which:—

Fig. 1 is an elevation of the blind roller and end journals; Fig. 2 an elevation of the complete blind fitted in position; Fig. 3 a section on the line 3—3 of Fig. 2; Fig. 4 an end view of a bearing bracket for one of the roller journals; and Fig. 5 a face view of the bearing bracket for the other roller journal.

Similar numerals refer to similar parts throughout the several views.

The blind roller 7 (Figs. 1 and 2) is of the type known as a split blind roller, in other words it has a longitudinal recess 8 in which one end of the blind 9 (Fig. 2) is detachably secured by a batten or the like (not shown). Each end journal 10 of the roller has a flange or collar 11, engaging the proximate end of the roller and an L-shaped bracket 12 secured to said flange or collar. When the end journal is in position the L-shaped bracket fits simply in the aforesaid recess 8 and is secured to the roller by a

screw 13 inserted through an opening in one limb of the bracket. For convenience in attaching the screw the head thereof may be formed with a polygonal opening 14 adapted to receive the end of a polygonal screw driver. One end journal 10 receives a flange or collar 15 in order to form between it and the adjacent collar 11 a cord drum 16, and the other end journal 10 has loosely mounted thereon a ratchet wheel 17 which is frictionally clutched to the journal by spring washers 18, 18 bearing one at either side thereof. One of the spring washers is accommodated between the ratchet wheel and the adjacent flange or collar 11, and the other spring washer is accommodated between the ratchet wheel and a collar 19 secured on the outer end of the journal.

Two brackets 20, 21 of novel construction are provided to receive the end journals 10, 10 of the blind roller. In practice, these brackets are attached to the window frame 22 (Fig. 2) in any suitable manner, as by means of screws 23.

As will be seen from Figs. 2, 3 and 4 the bracket 20 is channel shaped and on the outer limb 24 it carries an open jaw member 25 to receive that end journal 10 of the roller, which supports the ratchet wheel 17; whereas its other limb 26 projects forwardly on one side of the ratchet wheel. A detent 27 is pivoted at 28 between the two limbs 24, 26 and depends into the path of the ratchet wheel as the blind roller is rotated.

The other bracket 21 (Figs. 2 and 5) has flanges 29, 29 bent up one at each side of the bearing 30 for the end journal 10 carrying the cord drum 16, said flanges being so located as to overlap the collar 15 of said drum and being shaped to provide inclined guides for the blind cord 31.

Assuming the parts constituting the blind fitting have been assembled and that the complete blind has been erected in place then the operation is briefly as follows:—

When the blind is pulled down, the roller 7 is rotated but the ratchet wheel 17 is retained by reason of the detent 27 (which is forced into engagement with the jaw member 25) and, at the same time, the cord 31 winds itself on the cord drum 16. If, now, the cord 31 is pulled, the blind roller 7 is rotated in the opposite direction to raise the blind and owing to the frictional grip of the spring washers, the ratchet wheel is rotated with the roller slipping past the detent 27.

which comes into action immediately the cord is released to prevent the blind unwinding again of its own accord.

With certain roller blinds of the general character to which my invention belongs the blind cannot be equally spaced from either side of the window, owing to the drum for the operating cord being disposed between the aforesaid ratchet wheel and the adjacent end of the blind roller, whereby the fitting at that end of the roller is wider than the fitting at the other end. This disadvantage is eliminated by arranging the cord drum 16 at the end of the blind roller 7 remote from the ratchet wheel 17 thus providing end fittings of substantially equal width as will be apparent from Fig. 2.

By providing the flanges 29 on the bracket 21 so that they overlap the cord drum flange 20 or collar 15, the cord 31 is guided automatically back on to the drum 16 should it tend to free itself therefrom for any reason.

The limb 26 of the other bracket 20, 25 prevents axial movement of the blind roller by engaging the ratchet wheel 17 and thereby prevents accidental displacement of the roller from its bearings. Of course, the roller can be instantly detached by first 30 raising the left hand end journal 10 Fig. 2 from the jaw member 25 and then moving the roller bodily to the left to free the other end journal 10 from the bearing 30 in the bracket 21.

It will be apparent that the parts constituting the roller blind can be easily assembled and disassembled as and when required with a minimum of time and trouble and that the whole provides a simple roller 40 blind fitting which is not liable to get out of order.

The pivot pin 28 for the detent 27 is supported at both ends in openings in the limbs 24, 26 and for that reason cannot be bent or displaced during the operation of the blind.

Many modifications may be made without in any way departing from the scope of the invention; for example a single 50 spring washer 18 may be used for the ratchet wheel 17 but I find that when two such washers are employed as herein described and illustrated a more durable arrangement is obtained combined with a more 55 even action of the blind and blind roller. Further, the detent 27 and the ratchet wheel 17 may be reversed if it is preferred that the blind shall unwind itself on the other

side of the roller to that shown in Fig. 2, and the pivot pin 28 is located to suit either 60 position of the detent.

Having now fully described my invention what I claim and desire to secure by Letters Patent is:—

1. A blind roller, journals having discs 65 to bear against the end of the roller having flanges to embrace the peripheral surface thereof adjacent the ends, L-shaped brackets having their outstanding portions secured to the discs within the plane of the 70 flange and their lateral portions seated in recesses formed in the roller and of a depth materially exceeding the thickness of such lateral portions, a securing means passed through the lateral portions of the brackets 75 and engaging the roller, a ratchet wheel loosely arranged upon one of the journals, springs carried by the journal engaging the ratchet wheel on opposite sides thereof, the other journal being enlarged to provide a 80 cord drum.

2. In combination with a drum carrying journal of a blind roller, a bearing bracket having integral front and rear flanges with curved free edges to overlie the drum and 85 form inclined guides to cause the cord to wind upon the drum.

3. In combination with a journal of a blind roller formed in part to provide a cord drum and beyond the cord drum to form 90 a bearing spindle, a bracket to receive and support said bearing spindle, and guide members formed on the bracket on opposite sides of the spindle to project toward and overlie the adjacent end of the cord drum, 95 whereby to cause the cord to wind upon the drum in operation.

4. In combination with a journal of a blind roller formed in part to provide a cord drum and reduced beyond the cord 100 drum to form a spindle, a collar arranged upon the journal at the end of and having a diameter exceeding that of the cord drum, a bracket to receive and revolvably support the spindle, and flanges projecting inwardly 105 from the bracket to overlie the edges of the collar and project inwardly beyond the outer end of the cord drum, the operative edges of the flanges being curved, whereby 110 to cause the cord to wind upon the drum and prevent it from winding upon the spindle.

In testimony whereof I affix my signature.

CHARLES NEVATT.
